VALVE MECHANISM

Filed Nov. 29, 1926

UNITED STATES PATENT OFFICE.

THOMAS H. MOSELEY, OF OKLAHOMA CITY, AND CHARLES E. DROEGE, OF CUSHING, OKLAHOMA.

VALVE MECHANISM.

Application filed November 29, 1928. Serial No. 151,530.

This invention relates to valve mechanism and has special reference to means for automatically cutting off the flow of the liquid when the liquid attains a predetermined level in a tank or other receptacle. The invention also has for its object the provision of means whereby excessive opening of the cut off valve will be prevented and the closing of the valve will be effected expeditiously. The invention is illustrated in the accompanying drawing and will be herein-after fully set forth.

In the drawing:

Figure 1 is a sectional elevation of one embodiment of the invention;

Figs. 2 and 3 are enlarged sections through the cut-off valve taken in planes at a right angle to each other.

In the drawing, the reference numeral 1 indicates a reservoir or tank in which liquid is to be stored for use and 2 indicates a main supplying the said tank and having a branch 3 in which a valve casing 4 is interposed. Communicating with the main 2 at a point adjacent the branch 3 is a governor tank or receptacle 5 which is in communication with the supply main through a branch pipe 6 and which is so disposed that the level of the liquid therein will be the same as the level of the liquid in the main reservoir or tank 1. Housed within the governor tank 5 is a float 7 from which a gage bar or stem 8 rises, as shown, the said stem having openings 9 therethrough and extending at regular intervals throughout its height. The branch 3 communicates directly with the valve casing 4 and at a side of the casing opposite the pipe 10 which leads from the source of supply. Within the casing 4 is a partition 11 having a port 12 therethrough which may be closed by a valve 13. Carried by the lower side of the casing 4 and in axial alignment with the port 12 is a plug 14 which cooperates with a dashpot 15 on the under side of the valve 13 to cushion the closing movement of the valve and thereby avoid shock to the apparatus. The valve 13 is guided by the upper portion 17 of the valve casing and the valve stem 18 works in a sleeve or bonnet 16 secured upon and rising from the top 17 of the casing, the valve stem passing through the cap 19 which closes the top of the said guide or bonnet, and being thereby held to a rectilinear movement. It should be noted that the stem is free of

threads so that it merely slides relative to the cap 19 and is not caused to rotate by its engagement with the same. Secured upon the top 17 of the valve casing is a cylindrical housing 20 which rises from said top and is provided in one side with an obliquely disposed guide slot 21 and at its opposite side with an opening 22. A lever or handle member 23 is firmly secured to the valve stem 18 and passes at one side through the slot 21 to be guided thereby while at the other side it plays within the opening 22, a retractile spring 24 being attached to the handle member and the housing, as shown. Carried by the upper end of the housing 20 is a guide 25 which receives the upper end of the stem 18 and thereby prevents lateral movement of the latter, and threaded into the upper end of this guide in axial alinement with the stem is a stop screw 26 which may be adjusted longitudinally of the guide so as to be presented to the upper end of the stem and limit the upward movement of the same in an obvious manner, the said stop screw being provided with a handle 27 at its upper extremity, of any approved form. Secured rigidly to the stem 18 just below the guide 25 is a shoulder or abutment 28 which may be engaged by a latch 29 and is tapered upwardly, as shown. This latch 29 is illustrated as an L-shaped bar fulcrumed at its upper end on the upper edge of the housing 20 and having a lever or crank arm 30 fixed to its fulcrum and extending laterally therefrom, the said lever or crank arm being accommodated in a notch 31 in the upper edge of the housing and being constructed at its free end to pass around the gage bar 8 and aid in guiding the same. A pin 32 is provided to be engaged selectively in the openings 9 in the gage bar below the said lever or crank arm and to actuate the said element by impact against the under side of the same.

The operation of the apparatus will, it is thought, be readily understood from the foregoing description, taken in connection with the accompanying drawing. The weight of the valve cooperating with the tension of the spring 24 tends to hold the valve seated, and the handle 23, in the closed position of the valve, will be at the lower end of the inclined guide slot 21. The abutment 28 will be below the latch 29 and it will be noted that the edge of said abutment is beveled downwardly and outwardly so

that upon upward movement it will ride easily past the end of the latch and the vertical dimension of the abutment is such that in its lowest position the end of the latch will rest upon the edge of the abutment and will never project over the top of the abutment. When the tank 1 is to be filled, the handle 23 is swung sidewise and its engagement with the diagonally disposed 10 guide slot 21 will cause it to move upwardly at the same time, the stem 18 being thereby caused to rise and the valve lifted from its seat so that flow through the valve casing may occur. The upward movement of the 15 valve stem will carry the abutment 28 past the latch 29 and as soon as the abutment has cleared the latch the weight of the lever arm 30 will swing the latch into position under the abutment to engage and support the 20 same and maintain the valve in the open position, as shown by full lines in Fig. 3. The liquid will then flow into the reservoir or tank 1 and will simultaneously rise to the same level in the governor tank 5, and as 25 it rises in the governor tank the float 7 will be lifted so that an upward movement will be imparted to the gage bar 8. This upward movement will eventually bring the pin or stud 32 against the under side of the 30 lever 30 and will rock the lever so that the latch 29 will be swung outwardly from under the abutment 28, whereupon the spring 24 will at once retract and cooperate with the weight of the valve stem and the parts 35 carried thereby to quickly seat the valve and cut off the flow. As the liquid is withdrawn from the reservoir through use, the level of the liquid in the governor tank will simultaneously drop and the float 7 will descend so 40 that the latch will be returned to position to be engaged by the abutment 28 when the valve is again opened.

Our structure is exceedingly simple in construction and is certain in its operation so 45 that overflow of reservoirs will be prevented and waste of liquid thereby avoided. The apparatus may be advantageously employed

wherever a plurality of reservoirs are connected to one source of supply and it is desired to maintain the same level in all the 50 reservoirs, and it is to be understood that the drawing is illustrative only and not restrictive.

Having thus described the invention, we 55 claim:

1. In a valve mechanism, the combination of a valve casing, a housing rising from the valve casing and provided with an inclined slot in one wall, a valve mounted in the valve casing and having a stem rising 60 through the housing, a handle member secured to said stem and extending laterally therefrom through the inclined slot in the housing, a retractile spring attached to said handle and to the housing and tending to move the handle to valve-closing position, a shoulder on the valve stem above the handle, a latch mounted on the housing to engage the said shoulder when the valve is in open position, and float controlled means to release said latch and permit the valve to 70 close.

2. In a valve mechanism, the combination of a valve, a valve stem rising from the valve, means tending constantly to close the 75 valve, means for opening the valve, a shoulder on the valve stem, an upwardly tapered surface rising from the shoulder, a housing around the stem, a latch pivotally mounted on the housing and having its inner end 80 bearing against said tapered surface when the valve is in closed position and adapted to engage under the shoulder when the valve is in open position, an arm extending outwardly from the latch and having its end 85 free, and float-controlled means to impinge against and lift the outer free end of said arm whereby to release the latch and permit the valve to close.

In testimony whereof we affix our signatures.

THOMAS H. MOSELEY. [L. S.]
CHARLES E. DROEGE. [L. S.]
